[57] CLAIM

The ornamental design for a mouse pad with two interlocking pieces, as shown and described.

DESCRIPTION

FIG. 1 is an exploded perspective view of a mousepad with two interlocking pieces, the two halves are shown exploded for clarity of disclosure;

FIG. 2 is a top plan view thereof, on half of the mousepad is shown for ease of illustration, the bottom plan view is a mirror image, the other half of the mouse pad is identical; FIG. 3 is a side elevational view thereof, one half of the mousepad is shown for ease of illustration, the other half of the mousepad is identical;

FIG. 4 is an opposite side elevational view thereof, one half of the mousepad is shown for ease of illustration, the other half of the mousepad is identical;

FIG. 5 is an end elevational view thereof, one half of the mousepad is shown for ease of illustration, the other half of the mousepad is identical;

FIG. 6 is an opposite end elevational view thereof, one half of the mousepad is shown for ease of illustration, the other half of the mousepad is identical; and,

FIG. 7 is a top perspective view of the mousepad, showing the two halves of the mousepad interlocked.
